B. H. MATHIS

OIL TANK VALVE

Filed May 22, 1924

B. H. Mathis.

Inventor

By Adreas Dreyer his Attorney

UNITED STATES PATENT OFFICE.

BENEDICT H. MATHIS, OF WARREN, PENNSYLVANIA.

OIL-TANK VALVE.

Application filed May 22, 1924. Serial No. 715,126.

To all whom it may concern:

Be it known that I, BENEDICT H. MATHIS, a citizen of the United States, residing at Warren, in the county of Warren and State 5 of Pennsylvania, have invented certain new and useful Improvements in Oil-Tank Valves, of which the following is a specification.

This invention relates to a novel means of 10 discharging liquids from containers, and is especially directed to that form of containers placed on railroad cars and known as tank cars used in the transportation of oil and other liquids.

15 The primary object of this invention is to provide means for discharging substantially all of the liquid in a tank of the character described, even though one end of the tank may be temporarily positioned in a lower 20 plane than the plane of the discharge duct.

These and further objects will more fully appear from the following description in which reference will be had to the accompanying drawings which show a form of apparatus embodying the said inventions and 25 wherein:

Figure 1 is a tank with parts broken away, showing the application of invention.

Figure 2 is a sectional view of the valve 30 mechanisms.

Figure 3 shows a cross section of Figure 2. Referring to the accompanying drawings, 1 represents the tank for containing liquids, 2 is the discharge duct through which the 35 liquid is discharged. Located within the tank 1 and having discharging communication with the duct 2 is the tubular member 3. The lower end of the tubular member 3 is screw-threaded into the discharge duct 2. Located at the upper end of the tubular member 3 is a horizontally disposed barrel 4, internally apertured to receive the valve plug 5 formed with a cored interior cavity 6. The interior cavity 6 is provided with an 40 outlet port 7, which is placed in direct communication with the discharge duct 2 through the tubular member 3.

45 Adjacent to the ends of the valve plug 5, and positioned outside of the barrel 4 are the intake ports 8—8' positioned at 90° angles to the outlet port 7.

Operatively mounted for oscillating movement upon the valve plug 5 is the movable valve member 9.

55 The valve member 9 is of tubular formation comprising bi-furcated extensions 10—

10' adapted to straddle the barrel 4 and to form a sealed joint between the ends of the barrel 4 and the inner surfaces of the extensions 10—10'.

To provide for oscillating movement of the valve member 9 upon the valve plug 5 there is located in the extensions 10—10' the apertures 11—11' adapted to receive the valve plug 5. The apertures 11—11' are 60 taper bored to conform to a corresponding taper formed on the ends of the valve plug 5.

Located on the reduced tapered end of the valve plug 5 is the threaded stud 12 upon which is operatively mounted the nut 13 65 adapted to be set up to hold the valve parts in assembled position in a manner well known in the art.

Connected to the yoke of the tubular valve member 9 is the stand pipe 14, which is 70 maintained in the upright position shown in Figure 1 until it is desired to discharge the contents of the tank. Located on the upper end of the stand pipe 14, is the flexible member 15 which forms a continuation of the

75 conduit within the stand pipe 14. Surrounding the flexible member 15 is the coiled spring 19 which serves the functions of aligning the flexible member 15 with the stand pipe 14 as the stand pipe 14 is positioned horizontally along the floor of the bottom wall of the tank. Located on the 80 outlet end of the flexible member 15 is the swivel nozzle 16. By the application of the

85 swivel feature to the nozzle 16, the orifice of the nozzle will adjust itself to a position offering an unobstructed access of flow of the liquid in the bottom of the tank, through the flexible member 15 as the standpipe 14 is lowered to a horizontal position along the 90 bottom of the tank in the act of discharging, a function of the invention that will herein- 95 after be more fully explained. With the ordinary means heretofore employed in the art of discharging liquids from tanks of this character, when the oil or other liquid

100 reached a level with the discharge duct, the normal discharge flow would cease. If the tank car from which liquid was being thus discharged was positioned on an incline 105 causing one end of the tank to be lower than the discharge duct there would be left a considerable portion of the liquid in the end of the tank below the level of the discharge duct, which would fail of discharge by the 110 usual method employed.

One of the important functions of this in-

vention is to provide for the discharge of the liquid left in the lower end of the tank, after the normal flow as above explained, has ceased.

- 5 It will be obvious to those skilled in the art that upon lowering the standpipe 14 to a horizontal position along the bottom of the tank as diagrammatically shown in Figure 1, the flexible member 15 will extend itself 10 and place the nozzle 16 at a point near the extreme end of the tank. The nozzle 16 being formed with an L or side inlet, will by gravity assume a position placing its orifice at the lowest point in the tank.
- 15 As the standpipe 14 is lowered to the position above indicated, the oil or other liquid in the tank, will seek an outlet by passing into the standpipe 14 and the valve member 9. The valve member 9 being in a 20 horizontal position the ports 8-8' in the valve plug 5 will be uncovered and free passage will be allowed to the liquid to pass through the valve plug 5, the port 7 and the discharge duct 2, from which the oil or liquid will be conveyed to the usual containers 25 in a manner well known in the art.

It will be obvious to those skilled in the art, that should a tank from which the liquid is to be drawn be so positioned, that one 30 end thereof is lower than the centrally positioned discharge duct that by placing the nozzle 16 in the lowermost position of the tank the liquid remaining in the low end of the tank after the liquid has been drawn off to the level of the inlet of the discharge duct 2 and where a further discharge flow would 35 ordinarily cease, that in the present invention, the fluid will continue to be drawn from the tank through the siphoning effect induced by the positioning of the suction nozzle 16 at a point below the surface level of the liquid, but above the lower orifice of the discharge duct.

40 As the standpipe 14 is raised to a vertical position the ports 8-8' will be closed and no discharge of oil or liquid from the tank can occur.

45 For the purpose of maintaining the standpipe in a vertically disposed position, there

is provided the chain 17 attached by a suitable collar to the standpipe and adapted to be placed in holding engagement with the hook 18, positioned in the crown of the dome of the tank.

50 In the accompanying drawings, and in the foregoing description is set forth the preferred embodiment of the invention, but it will be obvious to those skilled in the art, that modifications thereof may be made without departing from the spirit of the invention. It is therefore to be understood that the present invention is not limited to the specific form of means shown.

55 What is claimed as new and is desired to be secured by Letters Patent is:

1. A tank discharging valve of the character described, comprising a valve head having a discharge port therein, a gudgeon passing through said valve head, a tubular passageway in said gudgeon in communication with said discharge port, a hollow yoke member spanning said valve head formed with ported yoke terminals rotatively mounted on said gudgeon, and closable ports in said gudgeon passageway adapted to be uncovered by the movement of the yoke member.

2. A tank discharging apparatus, comprising a valve boss having a discharge port therein, a valve head formed on said boss, a gudgeon positioned in said valve head having its ends extended therefrom, a cored conduit in said gudgeon in communication with said discharge port, a hollow yoke member formed with ported yoke terminals 85 rotatively mounted on said extended gudgeon ends, closable ports in the gudgeon passageway adapted to be uncovered by the movement of the yoke member, and a flexible tubular inlet member extending from said yoke member adapted to fold in a vertical plane as the yoke member is moved to close said ports, and to assume an extended position as the yoke member is positioned to open said ports.

90 In testimony whereof I have affixed my signature.

BENEDICT H. MATHIS.
